Primary Examiner—Alan P. Douglas*Assistant Examiner*—R. Spear*Attorney, Agent, or Firm*—Lyon & Lyon[57] **CLAIM**

The ornamental design for a carrier for bottles, as shown and described.

DESCRIPTION

FIG. 1 is a top plan view of a carrier for bottles showing my new design;

FIG. 2 is a front side elevational view thereof;

FIG. 3 is a right side elevational view thereof;

FIG. 4 is a bottom plan view thereof;

FIG. 5 is a cross sectional view of FIG. 1 taken along line 5—5; and,

FIG. 6 is a cross sectional view of FIG. 2 taken along line 6—6.

The rear side elevation view and the left side elevation view are omitted as being a mirror image of the respective front side elevation view of FIG. 2 and the right side elevation view of FIG. 3.

FIG. 1

FIG. 2

FIG. 3

FIG. 4

FIG. 6
